UNITED STATES PATENT OFFICE

THOMAS S. HUTCHISON, OF CHICAGO, ILLINOIS

GAME

Application filed March 16, 1932. Serial No. 599,147.

My invention pertains to a game in which spherical counters are projected one after another through a directing runway to a portion of a board employed for scoring purposes, the means employed to project said counters along said runway, consisting preferably of a spherical actuating member movable in a separate or operating runway and operated by a plunger so that the impact of the plunger on the actuating sphere, projects it along the operating runway, communicates its inertia by impact to a transfer mechanism, and the transfer mechanism by impact projects the one of the scoring counters in line with the transfer mechanism, through the directing runway in line with it, to the scoring portion of the board. By my invention I also provide a novel form of gate for holding the counters in the several scoring runways on the board, until all of the scoring counters have been played, after which the total score may be computed and then the gate may be moved by a slide bar, to release the scoring counters from the scoring runways and collect them in another portion of the movable gate, so that reverse movement of the slide bar is required to release the counters from the gate and permit them to roll to a position where they are again ready to be played. The gate referred to thus effectively lends itself to coin control, by providing the gate operating bar with an aperture for a coin and arranging the housing of the bar so that the latter must be pushed into the casing of the game as far as it will go to free the counters from the counting runways, which at the same time discharges the coin in the bar through an opening in the support for the bar, into the interior of the casing of the game, it being necessary to withdraw the bar from its innermost position, so that the gate may assume a position releasing the counters for further play. By my invention I preferably provide guide blocks and inclined surfaces between the gate and the playing position of the counters, so that the counters will line up without clogging, for operation one after another by the impact transferring devices.

My invention will best be understood by reference to the accompanying drawings

showing a preferred embodiment thereof, in which

Fig. 1 shows my game in plan view,

Fig. 2 is a vertical, sectional view through the structure shown in Fig. 1, taken along the line 2—2,

Fig. 3 is a right hand end view of the structure shown in Figs. 1 and 2,

Fig. 4 is a vertical, sectional view through the structure shown in Fig. 1, taken along the line 4—4,

Fig. 5 shows in plan view to an enlarged scale, the gate construction controlling the return of the counters to their playing position,

Fig. 6 is an end elevation of the gate shown in Fig. 5 and its attached operating arm,

Fig. 7 is a horizontal, sectional view to an enlarged scale, of a part of the structure shown in Fig. 2, taken along the line 7—7,

Fig. 8 is a horizontal, sectional view to an enlarged scale, of a part of the structure shown in Fig. 2, taken along the line 8—8,

Fig. 9 is a vertical, sectional view to an enlarged scale, of a part of the structure shown in Fig. 1, taken along the line 9—9,

Fig. 10 is a vertical, sectional view to an enlarged scale, of a part of the structure shown in Fig. 1, taken along the line 10—10, and

Fig. 11 is a vertical, sectional view to an enlarged scale, of a part of the structure shown in Fig. 1, taken along the line 11—11,

Similar numerals refer to similar parts throughout the several views.

As shown in Figs. 1 and 2, my game consists of a casing 10 of rectangular form, having a floor 11 which slopes from the front portion of the casing downwardly to the rear portion of said casing, at a substantial distance above the bottom wall of the casing, said floor being substantially level transversely of the casing, excepting at its rear end as will be described. A first partition wall 12 projects upwardly above the floor 11 substantially parallel with one side of the casing, to form a first runway 13 between said partition and the side wall of the casing, through which the spherical counters 33 are projected, one after another, 100

to deliver them to the portion of the floor 11 adjacent the front of the casing. A curved guide plate 14 is disposed at the delivery end of the runway 13, to direct the counters across the end portion of the floor 11 so that they may find their way to different ones of the counting runways, depending upon the velocity of the counters when they are projected from the runway 13. The floor 11 is also provided with partitions 15, 16, 17, 18, 19 and 20 extending above its upper surface and substantially parallel with the partition 12, to form scoring runways between the partitions 12 and 15, between said partitions 15-20 inclusive, and between the partition 20 and the vertical wall 21 at the side of the floor 11 remote from the runway 13. The front ends of the partitions 15-20 inclusive are preferably progressively farther from the front wall of the casing of the game than the front end of the partition 12, the other ends of the partitions 15-20 inclusive, being preferably in a plane extending transversely of the floor 11 and substantially perpendicular to the side walls of the casing. Resilient pins 22, are preferably supported by the floor 11 in vertical position adjacent the forward ends of the partitions 15-20 inclusive, to deflect the counters when the latter strike said pins. The partition 12 is somewhat higher than the partitions 15-20 inclusive, and extends at its rear end beyond the rear ends of said partitions 15-20 inclusive, and between the rear end of the partition 12 and the wall 21, a gate 23 is pivotally supported at 24 and 25 so that in its normal position, said gate retains the counters in the scoring runways into which they may find their way from the forward portion of the floor 11. As shown in Figs. 1, 5 and 6, the gate 23 consists of a continuous band of metal having a flat side 23a adjacent the rear ends of the partitions 15-20 inclusive, a curved side 23b curved to extend away from the side 23a and towards the rear portion of the game, and short parallel end portions 23c and 23d engaging the pivotal supports 24 and 25 of the gate. The end portion 23d has rigidly secured to it, a downwardly extending arm 26 which projects through a clearance opening therefor in the floor 11, the lower end of said arm being connected as indicated in Fig. 2, by a spring 27 with the under side of the floor 11 as indicated at 28, so that the tension of the spring 27 holds the arm 26 against a stop pin 29 carried by the wall 21, when the gate is not actuated to release the counters from the counting runways, this being the normal position of the gate. As shown in Fig. 2, the gate 23 in its normal position is inclined downwardly adjacent the rear ends of the partitions 15-20 inclusive, to hold the counters in the counting runways, the curved side 23b of said gate, being at that time high enough above the floor 11 to permit the counters to pass freely under

the side 23b to the lower rear part of the floor 11. When the arm 26 is moved away from the stop pin 29 sufficiently to raise the side 23a of the gate to release the counters from the counting runways, the side 23b of the gate is lowered sufficiently so that the counters roll into and are enclosed within the gate between its side walls, and held in that position until the gate is permitted to return to its normal position.

A block 30 is secured to the floor 11 at its rear end adjacent the wall 21, said block having a beveled end adjacent the gate 23, to direct the counters from adjacent the wall 21 towards the mid portion of the rear end of the floor. A second and triangular block 31 is secured to the floor 11 with one of its shorter sides spaced from the side wall of the casing to continue the runway 13 to the rear end of the floor 11, the other shorter side of the block being spaced from a vertical wall 32 across the rear end of the floor 11, to form a transverse runway for the counters 33, to direct them one after another, to the rear end of the runway 13 as shown for the counter 33a, which is in position to be projected along the runway 13 by operating mechanism to be described. The rear edge of the block 31 is beveled as indicated at 31a, so that its highest portion is adjacent the runway 13, and that it slopes downwardly towards the mid portion of the rear end of the floor 11, to assist in directing the counters 33 to the transverse runway referred to and insure that they will line up without clogging, for movement successively into line with the runway 13, as said counters are projected one after the other through said runway 13. The long edge of the block 31 constitutes a guide for the counters released by the gate 23, and directs the counters towards the block 30 and this aids in preventing jamming of the counters as they line up in the transverse runway referred to. A horizontal pin or rod 34 is preferably supported by the block 30 diagonally across the corner between it and the wall 32, to prevent any of the counters from lodging in said corner and so failing to roll into the transverse runway referred to. The surface of the floor 11 adjacent the wall 32, is preferably cut away as more clearly shown at 11a in Fig. 9, to incline the bottom of the transverse runway downwardly towards the rear end of the runway 13, so that the counters 33 will roll down the transverse runway to the position indicated by the counter 33a, one after the other as the preceding counters are projected through the runway 13. The block 31 is proportioned so that its angle adjacent the gate 23, is spaced from said gate and from the rear end of the partition 12 sufficiently to permit the counters to roll between the block 31 and the rear end of the partition 12 and also between said block and the gate 23. A deflecting member 35 is dis-

posed across the runway 13 at the angle of the block 31 referred to, which moves freely to permit practically unrestricted movement of the counters projected along the runway 13, said member moving to its position of rest after the passage of a counter, so that in the event the counter is not projected from the runway 13, when it rolls down said runway towards the rear end of the floor 11, it will be directed by the deflecting member 35 along the long side of the block 31 and to the rear end of the line of counters in the transverse runway, so that it may again be projected through the runway 13. The discharge end of the runway 13 near the front end of the floor 11, is provided with a deflecting member 36 supported in inclined position, to permit the counters to pass freely from the runway 13, and prevent their returning to the runway if they are projected with sufficient force to rebound from the wall 21 towards the runway 13. Each of the deflecting members 35 and 36 may conveniently be constructed as shown for the deflecting member 35 in Fig. 11. As shown in said figure, the deflecting member consists of a bent wire support 35a having a horizontally extending arm 35b on which the deflecting member is pivotally supported so that it may be easily lifted by the counters passing it in one direction, and prevent the passage of the counters when moving in the opposite direction, the arm 35b being sufficiently above the floor 11 to permit the counters to pass freely under it. The deflecting member 35 may consist of a bent wire having eyes formed at its ends which loosely engage the arm 35b, the member being in the form of a loop hanging from the arm 35b, and preferably provided at one side with an extending portion 35c to engage the support 35a and limit opening movement of the deflecting member 35 to one direction, so that the counters may freely pass under the arm 35b for one direction of motion longitudinally of the runway 13, and be prevented from passing the deflecting member 35 for reversed movement longitudinally of the runway 13, the inclined relation of the deflecting member transversely of the floor 11, serving to direct the counters moving rearward in the runway adjacent the partition 12, to the long side of the block 31 as above described. The arm 35b is preferably continued beyond the eyes of the deflecting member 35 and bent to extend substantially parallel with the supporting portion of said arm, as shown at 35d, to prevent upward movement of the deflecting member beyond a point where it will fall freely by gravity, after a counter operating it has passed it, thus preventing the deflecting member from becoming inoperative. The portion 35d is preferably provided with a bent end 35e engaging the arm 35b adjacent one of the eyes of the deflecting member 35,

to prevent longitudinal movement of the deflecting member 35 on the arm 35b, to a position rendering the deflecting member inoperative. The lower portion of the deflecting member 35 is sufficiently above the floor 11 to engage the mid portion of the counters, to the end that the deflector may conveniently perform its intended functions.

As more clearly shown in Figs. 7 and 10, the partition 12 is preferably in the form of an angle bar extending through a corresponding slot therefor in the floor 11, the horizontal portion 12a of said angle bar resting against and being secured to the bottom surface of the floor 11 in any convenient manner, for example by screws as indicated. As also shown in these figures, the partitions 15 and 16 are preferably the flange members of a U-shaped bar 15a secured to the lower surface of the floor 11 in any convenient manner, for example by screws as indicated, the flanges of said U-shaped bar, extending through suitable slots in the floor 11 to receive them. The partitions 17 and 18 are preferably flanges of a similar U-shaped bar 17a and the partitions 19 and 20 are preferably flanges of a U-shaped bar 19a, which U-shaped bars 17a and 19a are similarly secured to the floor, with their flanges extending through the floor in the same manner described for the flanges of the U-shaped bar 15a.

As shown in Fig. 7, below the supporting portions of the partitions 12 and 15-20 inclusive, a transverse mounting bar 37 is supported by having its ends secured to the wall 21 and to the casing of the game. An operating lever 38 is pivotally mounted at 39 on the bar 37, said lever having downwardly extending ends 38a and 38b. The end 38b is connected by a link 40 with the lower end of the arm 26, so that movement of the end 38a of the lever towards the rear of the casing, will rock the gate 23 on its pivotal supports against the action of the spring 27 as above described.

The game described is conveniently adapted for coin control, which may be accomplished by mounting a coin slide 41 in the front wall of the casing, in a suitable supporting guide 42 rigidly secured to the front wall of the casing, so that the said slide 41 may be reciprocated horizontally. The slide is mounted so that when it is moved to its innermost position, its inner end will engage and move the downwardly extending end 38a of the lever 38, towards the rear of the casing, and accomplish the operation of the gate above described. It is to be noted that the slide 41 does not in any way engage the lever 38, there being no mechanical connection between the slide and the lever, until the slide is nearly in its innermost position, at which time the engagement between the slide and the extending end 38a takes place, and

only a relatively small amount of movement of the slide 41 is required to rock the gate 23 to release the counters 33. The slide 41 is provided with an aperture 43 through it, to receive the coin or token employed to control the operation of the game, and the slide support 42 is provided with a discharge aperture 44 for the coin, so that the slide 41 must be in its extreme inner position before the aperture 43 registers with the aperture 44, and the coin or token in the slide 41 is permitted to drop therefrom through the supporting structure 42 into the bottom part of the casing of the game. The coin controlling mechanism described is preferably provided with devices usual in connection with such structures, for requiring a full stroke of the slide 41 after a coin or token is placed in it and the slide has been moved part way towards the rear of the casing, as well as devices preventing movement of the slide 41 to its extreme inner position unless a coin or token is in the aperture 43. These safety devices are well known in the art and as I do not claim the safety devices referred to as a part of my present invention, they are not shown and described. Where the game is controlled by coin apparatus of any kind, the front wall of the casing is preferably provided with a door or removable panel 45 as shown in Fig. 3, provided with a lock 46 normally holding the same in closed condition, so that the coins or tokens deposited in the game may be removed only by an authorized person.

An important part of my game consists of the novel means employed for projecting the counters 33, one after another, from the position shown at 33a in Fig. 1, upwardly along the runway 13. This counter projecting mechanism is in part similar to counter projecting mechanism shown and described in my United States Letters Patent No. 1,772,006, but as embodied in the present construction, it has a mode of operation not found in said patent, which materially contributes to the effectiveness of my present game. As shown in Fig. 1, the wall 21 is spaced from the adjacent side wall of the casing to form an operating runway 47, which, as more clearly shown in Fig. 4, is inclined upwardly from front to rear of the casing of the game. An operating member 48 in the form of a sphere, is located in the runway 47 for engagement when in playing position, by the inner end of a rod or plunger 49 which is mounted for longitudinal movement in a supporting member 50 carried by the front wall of the casing. The outer end 60 of the plunger 49 has secured thereto a handle 51 by means of which the plunger 49 may be operated as desired. The inner end of the plunger 49 is preferably provided with a tip 52 of material that is somewhat resilient and adapted to withstand the impact between it

and the sphere 48. When the plunger 49 is moved outwardly from its position indicated in Figs. 1 and 4, the sphere 48 rolls a short distance down the runway 47 and into engagement with a stop pin 53 which may conveniently extend horizontally across the runway just above the path of movement of the plunger 49 and a distance above the bottom of the runway 47 to engage the upper portion of the sphere 48. The plunger 49 is purposely given a range of movement much greater than the small movement permitting the sphere 48 to engage the pin 53, so that the force exerted upon the sphere 48 to move it towards the rear end of the runway 47, is by a quick movement of the plunger, which by impact imparts sufficient energy to the sphere 48 to move it forcibly to the extreme rear end of the runway 47. This quick movement of the plunger 49 may be effected directly by the player of the game if desired, or if preferred, the plunger 49 may have mounted upon it, a spring 54 between a washer 55 resting against the end of the supporting structure 50, and a second washer 56 held in place on the plunger 49 by a pin 57. Where such a spring is used to impart quick movement to the plunger inwardly, I find it desirable to provide a washer 58 of resilient material between the handle 51 and the supporting structure 50, to cushion the impact of the plunger at the extreme end of its inner movement, and thus reduce the noise that would otherwise result and the jar that would otherwise be communicated to the other parts of the plunger structure.

As more clearly shown in Fig. 8, a lever 59 is mounted in a generally horizontal position between the wall 32 and the rear wall of the casing of the game, and is pivotally supported at 60 on a bracket 61 secured to the wall 32. One end of the lever 59 carries a resilient bumper 62 in the rear end of the runway 47, for engagement by the sphere 48 when it is projected rearwardly in said runway, and the other end of said lever, carries a rod 63 in line with and extending towards the runway 13, the forward end of said rod being preferably provided with a tip 63a of material sufficiently resilient and of a nature to withstand the impact of said tip against the counters. An aperture 32a is provided in the wall 32, to clear the forward end of the rod 63. The end portion of the lever 59 adjacent the rod 63 is preferably slotted as indicated at 59a so that the rod 63 may be moved to any desired position in the lever 59 and there held by a clamping screw 64, permitting adjustment of the rod to impart desired impact to the playing counter 33a to drive it through the runway 13 to the upper end of the floor 11. Resilient stops 65 and 66 are preferably provided on the wall 32 and the rear wall of the casing, to limit movement of the lever 59, and the lever is

preferably held in the position indicated in Fig. 8, by a spring 67 secured at one end to said lever, and having its other end pressing against the wall 32. A plate 68 is preferably mounted on the inner surface of the side wall of the casing adjacent the playing counter 33a, to give the playing counter exact position and to quickly free it from side friction with the wall of the casing, when it is projected from playing position by the rod 63. A pin 69 is preferably disposed horizontally across the rear end of the operating runway 47, at a height to clear the sphere 48 when it engages the bumper 62 to prevent upward rebound of the sphere 48 from the bumper, projecting the sphere 48 upwardly and out of the operating runway 47. It will be observed that the rear end of the runway 13 is lower than the rear end of the runway 47, and since the bumper 62 is in line with the rear end of the runway 47, and the rod 63 is in line with the rear end of the runway 13, the lever 59 is inclined somewhat to a horizontal position to effectively communicate the energy of the sphere 48 to the playing counter 33a. The rod 63 is preferably adjusted so that when the lever 59 is in the position indicated in Fig. 8, the tip 63a is not in engagement with the playing counter 33a. This results in the energy imparted to the plunger 49 either by the player, or by the spring 54, being communicated to the playing counter 33a, by a succession of impacts, first the impact of the tip 52 against the operating sphere 48, second the impact of the sphere 48 against the bumper 62 and third, the impact of the tip 63a against the playing counter 33a. These several impacts introduce sufficient uncertainty into the play of the game to make it interesting, and yet much of the result of the play of the game is determined by the skill with which the plunger 49 is operated. Furthermore, the result of operating the plunger 49 where the spring 54 is employed, is determined in considerable measure by the manner in which the handle 51 is released, even for the same amount of compression of the spring 54, that is to say, a quick release of the handle 51 will impart considerably more impact to the sphere 48 and so to the playing counter 33a, than if the handle 51 is permitted to move more slowly from the fingers of the player. These factors of operation together with the hazards represented by the placing of the partitions 15-20 inclusive and the resilient pins 22, combine to produce a game of much interest. Where the gate 23 is operated by coin controlled devices as described, the casing 10 is provided with a glass top wall completely enclosing the parts of the game excepting the coin slide 41 and the handle 51, since the latter parts are the only parts of the game that need to be handled at any time by the player.

While I have shown my invention in the particular embodiment above described, it will be understood that I do not limit myself to this exact construction as I may employ equivalents known to the art at the time of the filing of this application without departing from the scope of the appended claims.

What I claim is:

1. In a game, the combination of a casing having side, end and bottom walls, a floor above said bottom wall and inclined downwardly from front to rear of said casing, spaced partitions extending lengthwise of and above said floor and defining a counter projecting runway at one side of said floor and substantially parallel scoring runways spaced from the front end wall of said casing, a side partition wall extending lengthwise of and above said floor and defining one side of the scoring runway most remote from said projecting runway, the rear ends of said scoring runways terminating in a plane extending across said floor near the mid portion lengthwise of said floor, spherical counters, a gate extending across the rear ends of said scoring runways and pivotally supported at its ends and movable to counter holding and counter releasing positions, a spring connected with said gate and tending to hold said gate in its position holding said counters in said scoring runways, devices for moving said gate to its counter releasing position, an end partition wall extending transversely across and above the rear end of said floor and spaced from the rear end of said casing, said floor being inclined downwardly laterally adjacent said end partition wall towards the rear end of said projecting runway and constituting a transverse runway directing counters released by said gate towards the rear end of said projecting runway, and counter projecting mechanism between said end partition wall and the rear end of said casing and having a member for movement against a counter in the rear end of said projection runway.

2. In a game, the combination of a casing having side, end and bottom walls, a floor above said bottom wall and inclined downwardly from front to rear of said casing, spaced partitions extending lengthwise of and above said floor and defining a counter projecting runway at one side of said floor and substantially parallel scoring runways spaced from the front end wall of said casing, a side partition wall extending lengthwise of and above said floor and defining one side of the scoring runway most remote from said projecting runway, the rear ends of said scoring runways terminating in a plane extending across said floor near the mid portion lengthwise of said floor, spherical counters, a gate extending across the rear ends of said scoring runways and pivotally supported at its ends and movable to counter

holding and counter releasing positions, a first spring connected with said gate and tending to hold said gate in its position holding said counters in said scoring runways, devices for moving said gate to its counter releasing position, an end partition wall extending transversely across and above the rear end of said floor and spaced from the rear end of said casing, said floor being inclined downwardly laterally adjacent said end partition wall towards the rear end of said projecting runway and constituting a transverse runway directing counters released by said gate towards the rear end of said projecting runway, and counter projecting mechanism between said end partition wall and the rear end of said casing and having a member for movement against a counter in the rear end of said projection runway, said projecting mechanism comprising a pivotally mounted lever extending transversely of said casing between its rear end and said end partition wall and carrying said member, a second spring engaging said lever and tending to hold said member away from a counter to be projected, and impact devices for operating said lever, said side partition wall being spaced from the adjacent side of said casing and forming an operating runway inclined upwardly from front to rear of said casing, a portion of said lever extending into the rear end of said operating runway, said impact devices comprising an operating sphere in said operating runway, and a rod movable longitudinally in the front portion of said operating runway to operate said operating sphere. 70

an operating runway inclined upwardly from front to rear of said casing, a portion of said lever extending into the rear end of said operating runway, said impact devices comprising an operating sphere in said operating runway, a rod movable longitudinally in the front portion of said operating runway to operate said operating sphere, and a stop extending into the path of said operating sphere in the front portion of said operating runway and out of the path of travel of said rod, whereby said rod may be retracted a substantial distance from said operating sphere before being moved to strike said operating sphere.

5. In a game, the combination of a casing having side, end and bottom walls, a floor above said bottom wall and inclined downwardly from front to rear of said casing, spaced partitions extending lengthwise of and above said floor and defining a counter projecting runway at one side of said floor and substantially parallel scoring runways spaced from the front end wall of said casing, 20 a side partition wall extending lengthwise of and above said floor and defining one side of the scoring runway most remote from said projecting runway, the rear ends of said scoring runways terminating in a plane extending across said floor near the mid portion lengthwise of said floor, spherical counters, a gate extending across the rear ends of said scoring runways and pivotally supported at its ends and movable to counter holding 25 30 35 40 45 50 55 60 65 70 75 80 85 90 95 100 and counter releasing positions, a first spring connected with said gate and tending to hold said gate in its position holding said counters in said scoring runways, devices for moving said gate to its counter releasing position, an end partition wall extending transversely across and above the rear end of said floor and spaced from the rear end of said casing, said floor being inclined downwardly laterally adjacent said end partition wall towards the rear end of said projecting runway and constituting a transverse runway directing counters released by said gate towards the rear end of said projecting runway, and counter projecting mechanism between said end partition wall and the rear end of said casing and having a member for movement against a counter in the rear end of said projection runway, said projecting mechanism comprising a pivotally mounted lever extending transversely of said casing between its rear end and said end partition wall and carrying said member, a second spring engaging said lever and tending to hold said member away from a counter to be projected, and impact devices for operating said lever, said side partition wall being spaced from the adjacent side of said casing and forming an operating runway inclined upwardly from front to rear of said casing, a portion of said lever extending into the rear

end of said operating runway, said impact devices comprising an operating sphere in said operating runway, a rod movable longitudinally in the front portion of said operating runway to operate said operating sphere, a supporting guide for said rod carried by said casing, and a third spring tending to hold said rod in its rear position.

6. In a game, the combination of a casing having side, end and bottom walls, a floor above said bottom wall and inclined downwardly from front to rear of said casing, spaced partitions extending lengthwise of and above said floor and defining a counter projecting runway at one side of said floor and substantially parallel scoring runways spaced from the front end wall of said casing, a side partition wall extending lengthwise of and above said floor and defining one side of the scoring runway most remote from said projecting runway, the rear ends of said scoring runways terminating in a plane extending across said floor near the mid portion lengthwise of said floor, spherical counters, a gate extending across the rear ends of said scoring runways and pivotally supported at its ends and movable to counter holding and counter releasing positions, a spring connected with said gate and tending to hold said gate in its position holding said counters in said scoring runways, devices for moving said gate to its counter releasing position, an end partition wall extending transversely across and above the rear end of said floor and spaced from the rear end of said casing, said floor being inclined downwardly laterally adjacent said end partition wall towards the rear end of said projecting runway and constituting a transverse runway directing counters released by said gate towards the rear end of said projecting runway, counter projecting mechanism between said end partition wall and the rear end of said casing and having a member for movement against a counter in the rear end of said projection runway, and guide blocks on the rear portion of said floor for directing counters to the mid portion of the rear end of said floor and to said transverse runway.

7. In a game, the combination of a casing having side, end and bottom walls, a floor above said bottom wall and inclined downwardly from front to rear of said casing, spaced partitions extending lengthwise of and above said floor and defining a counter projecting runway at one side of said floor and substantially parallel scoring runways spaced from the front end wall of said casing, a side partition wall extending lengthwise of and above said floor and defining one side of the scoring runway most remote from said projecting runway, the rear ends of said scoring runways terminating in a plane extending across said floor near the mid portion lengthwise of said floor, spherical count-

ers, a gate extending across the rear ends of said scoring runways and pivotally supported at its ends and movable to counter holding and counter releasing positions, a spring connected with said gate and tending to hold said gate in its position holding said counters in said scoring runways, devices for moving said gate to its counter releasing position, an end partition wall extending transversely across and above the rear end of said floor and spaced from the rear end of said casing, said floor being inclined downwardly laterally adjacent said end partition wall towards the rear end of said projecting runway and constituting a transverse runway directing counters released by said gate towards the rear end of said projecting runway, counter projecting mechanism between said end partition wall and the rear end of said casing and having a member for movement against a counter in the rear end of said projection runway, and guide blocks on the rear portion of said floor for directing counters to the mid portion of the rear end of said floor and to said transverse runway, a first one of said blocks defining in part said transverse runway and the rear portion of said projecting runway.

8. In a game, the combination of a casing having side, end and bottom walls, a floor above said bottom wall and inclined downwardly from front to rear of said casing, spaced partitions extending lengthwise of and above said floor and defining a counter projecting runway at one side of said floor and substantially parallel scoring runways spaced from the front end wall of said casing, a side partition wall extending lengthwise of and above said floor and defining one side of the scoring runway most remote from said projecting runway, the rear ends of said scoring runways terminating in a plane extending across said floor near the mid portion lengthwise of said floor, spherical counters, a gate extending across the rear ends of said scoring runways and pivotally supported at its ends and movable to counter holding and counter releasing positions, a spring connected with said gate and tending to hold said gate in its position holding said counters in said scoring runways, devices for moving said gate to its counter releasing position, an end partition wall extending transversely across and above the rear end of said floor and spaced from the rear end of said casing, said floor being inclined downwardly laterally adjacent said end partition wall towards the rear end of said projecting runway and constituting a transverse runway directing counters released by said gate towards the rear end of said projecting runway, counter projecting mechanism between said end partition wall and the rear end of said casing and having a member for movement against a counter in the rear end of said projection runway.

runway, guide blocks on the rear portion of said floor for directing counters to the mid portion of the rear end of said floor and to said transverse runway, a first one of said blocks defining in part said transverse runway and the rear portion of said projecting runway, there being a counter passageway opening from said projecting runway and extending along the side of said first block remote from said projecting runway, and a deflecting member across said projecting runway adjacent said opening and freely movable by counters projected in said projecting runway, said deflecting member directing into said passageway counters rolling down said projecting runway.

9. In a game, the combination of a casing having side, end and bottom walls, a floor above said bottom wall and inclined downwardly from front to rear of said casing, spaced partitions extending lengthwise of and above said floor and defining a counter projecting runway at one side of said floor and substantially parallel scoring runways spaced from the front end wall of said casing, a side partition wall extending lengthwise of and above said floor and defining one side of the scoring runway most remote from said projecting runway, the rear ends of said scoring runways terminating in a plane extending across said floor near the mid portion lengthwise of said floor, spherical counters, a gate extending across the rear ends of said scoring runways and pivotally supported at its ends and movable to counter holding and counter releasing positions, a spring connected with said gate and tending to hold said gate in its position holding said counters in said scoring runways, devices for moving said gate to its counter releasing position, an end partition wall extending transversely across and above the rear end of said floor and spaced from the rear end of said casing, said floor being inclined downwardly laterally adjacent said end partition wall towards the rear end of said projecting runway and constituting a transverse runway directing counters released by said gate towards the rear end of said projecting runway, and counter projecting mechanism between said end partition wall and the rear end of said casing and having a member for movement against a counter in the rear end of said projection runway, said gate comprising an endless metal band having front, rear and end portions, said end portions engaging the pivotal supports of said gate, an arm extending vertically from one of said gate end portions and connected with said spring, and a stop limiting movement of said arm and said gate under the action of said spring to an inclined position holding said gate front portion in the path of counters in said scoring runways and holding said gate rear portion above said floor in counter 130

- clearing position, said gate rear portion being distended rearwardly, whereby movement of said gate against the action of said spring moves said gate front portion to counter clearing position and also moves said gate 5 rear portion to counter engaging position collecting within said gate counters released from said scoring runways and reverse movement of said gate by said spring releases the counters collected in said gate.
10. In a game, the combination of a casing having side, end and bottom walls, a floor above said bottom wall and inclined downwardly from front to rear of said casing, spaced partitions extending lengthwise of and above said floor and defining a counter projecting runway at one side of said floor and substantially parallel scoring runways spaced from the front end wall of said casing, a side partition wall extending lengthwise of and above said floor and defining one side of the scoring runway most remote from said projecting runway, the rear ends of said scoring runways terminating in a plane extending across said floor near the mid portion lengthwise of said floor, spherical counters, 70 a gate extending across the rear ends of said scoring runways and pivotally supported at its ends and movable to counter holding and counter releasing positions, a spring connected with said gate and tending to hold said gate in its position holding said counters in said scoring runways, devices for moving said gate to its counter releasing position, an end partition wall extending transversely across and above the rear end of said floor 80 and spaced from the rear end of said casing, said floor being inclined downwardly laterally adjacent said end partition wall towards the rear end of said projecting runway and constituting a transverse runway directing 85 counters released by said gate towards the rear end of said projecting runway, and counter projecting mechanism between said end partition wall and the rear end of said casing and having a member for movement 90 against a counter in the rear end of said projection runway, said gate comprising an endless metal band having front, rear and end portions, said end portions engaging the pivotal supports of said gate, 95 an arm extending vertically from one of said gate end portions and connected with said spring, and a stop limiting movement of said arm and said gate under the action of said spring to an inclined position holding said gate front portion in the path of counters in said scoring runways and holding said gate rear portion above said floor in counter clearing position, said gate 100 rear portion being distended rearwardly, whereby movement of said gate against the action of said spring moves said gate front portion to counter clearing position and also moves said gate rear portion to counter engaging position collecting within said gate 105 counters released from said scoring runways and reverse movement of said gate by said spring releases the counters collected in said gate, said gate moving devices comprising a lever connected with said gate arm, a bar movable lengthwise of said casing and extending through a wall thereof for operation by a player, and a support for said bar, said bar being in line with the operating portion of said lever and pressing against the latter during a portion of the movement of said bar in one direction, said lever and said bar being free from mechanical operating connections. 110
11. In a game, the combination of a casing having side, end and bottom walls, a floor above said bottom wall and inclined downwardly from front to rear of said casing, spaced partitions extending lengthwise of and above said floor and defining a counter 115
12. In a game, the combination of a cas- 120

ing having side, end and bottom walls, a floor above said bottom wall and inclined downwardly from front to rear of said casing, spaced partitions extending lengthwise of and above said floor and defining a counter projecting runway at one side of said floor and substantially parallel scoring runways spaced from the front end wall of said casing, a side partition wall extending lengthwise of and above said floor and defining one side of the scoring runway most remote from said projecting runway, the rear ends of said scoring runways terminating in a plane extending across said floor near the mid portion lengthwise of said floor, spherical counters, a gate extending across the rear ends of said scoring runways and pivotally supported at its ends and movable to counter holding and counter releasing positions, a spring connected with said gate and tending to hold said gate in its position holding said counters in said scoring runways, devices for moving said gate to its counter releasing position, an end partition wall extending transversely across and above the rear end of said floor and spaced from the rear end of said casing, said floor being inclined downwardly laterally adjacent said end partition wall towards the rear end of said projecting runway and constituting a transverse runway directing counters released by said gate towards the rear end of said projecting runway, and counter projecting mechanism between said end partition wall and the rear end of said casing and having a member for movement against a counter in the rear end of said projection runway, said gate having an extending arm, said gate moving devices comprising a lever connected with said gate arm, a bar movable lengthwise of said casing and extending through a wall thereof for operation by a player, and a support for said bar, said bar being in line with the operating portion of said lever and pressing against the latter during a portion of the movement of said bar in one direction, said lever and said bar being free from mechanical operating connections, said bar and its support comprising parts of coin controlled mechanism.

13. In a game, the combination of a casing having side, end and bottom walls, a floor above said bottom wall and inclined downwardly from front to rear of said casing, spaced partitions extending lengthwise of and above said floor and defining a counter projecting runway at one side of said floor and substantially parallel scoring runways spaced from the front end wall of said casing, a side partition wall extending lengthwise of and above said floor and defining one side of the scoring runway most remote from said projecting runway, the rear ends of said scoring runways terminating in a plane extending across said floor near the mid por-

tion lengthwise of said floor, spherical counters, a gate extending across the rear ends of said scoring runways and pivotally supported at its ends and movable to counter holding and counter releasing positions, a spring connected with said gate and tending to hold said gate in its position holding said counters in said scoring runways, devices for moving said gate to its counter releasing position, an end partition wall extending transversely across and above the rear end of said floor and spaced from the rear end of said casing, said floor being inclined downwardly laterally adjacent said end partition wall towards the rear end of said projecting runway and constituting a transverse runway directing counters released by said gate towards the rear end of said projecting runway, and counter projecting mechanism between said end partition wall and the rear end of said casing and having a member for movement against a counter in the rear end of said projection runway, said gate comprising an endless metal band having front, rear and end portions, said end portions engaging the pivotal supports of said gate, an arm extending vertically from one of said gate end portions and connected with said spring, and a stop limiting movement of said arm and said gate under the action of said spring to an inclined position holding said gate front portion in the path of counters in said scoring runways and holding said gate rear portion above said floor in counter clearing position, said gate rear portion being distended rearwardly, whereby movement of said gate against the action of said spring moves said gate front portion to counter clearing position and also moves said gate rear portion to counter engaging position collecting within said gate counters released from said scoring runways and reverse movement of said gate by said spring releases the counters collected in said gate, said gate moving devices comprising a lever connected with said gate arm, a bar movable lengthwise of said casing and extending through a wall thereof for operation by a player, and a support for said bar, said bar being in line with the operating portion of said lever and pressing against the latter during a portion of the movement of said bar in one direction, said lever and said bar being free from mechanical operating connections, said bar and its support comprising parts of coin controlled mechanism.

14. In a game, the combination of a casing having a floor inclined downwardly from front to rear of said casing, spherical counters for movement on said floor, scoring runways and a counter projecting runway on said floor, an operating runway, an operating sphere in said operating runway, a member for movement longitudinally of said operating runway for operating said operating sphere, impact transferring devices extending

from the rear end of said operating runway to the rear end of said projecting runway, and a movable gate across the outlet ends of said scoring runways.

15. In a game, the combination of a casing having a floor inclined downwardly from front to rear of said casing, spherical counters for movement on said floor, scoring runways and a counter projecting runway on said floor, an operating runway, an operating sphere in said operating runway, a member for movement longitudinally of said operating runway for operating said operating sphere, impact transferring devices extending from the rear end of said operating runway to the rear end of said projecting runway, and a movable gate across the outlet ends of said scoring runways, said impact transferring devices comprising a pivotally mounted lever having one of its ends in line with said operating runway and its other end in line with said projecting runway, and a spring tending to move said one end of said lever towards said operating runway.

25. 16. In a game, the combination of a casing having a floor inclined downwardly from front to rear of said casing, spherical counters for movement on said floor, scoring runways and a counter projecting runway on said floor, an operating runway, an operating sphere in said operating runway, a member for movement longitudinally of said operating runway for operating said operating sphere, impact transferring devices extending from the rear end of said operating runway to the rear end of said projecting runway, and a movable gate across the outlet ends of said scoring runways, said impact transferring devices comprising a pivotally mounted lever having one of its ends in line with said operating runway and its other end in line with said projecting runway, a spring tending to move said one end of said lever towards said operating runway, a rod extending from said other end of said lever towards said projecting runway and movable relatively to said lever for adjustment purposes, and clamping means for holding said rod in desired adjustment relatively to said lever.

50. 17. In a game, the combination of a casing having a floor inclined downwardly from front to rear of said casing, spherical counters for movement on said floor, scoring runways and a counter projecting runway on said floor, an operating runway, an operating sphere in said operating runway, a member for movement longitudinally of said operating runway for operating said operating sphere, impact transferring devices extending from the rear end of said operating runway to the rear end of said projecting runway, a movable gate across the outlet ends of said scoring runways, an arm carried by and extending from said gate, and a bar ex-

tending through said casing and movable to operate said arm.

18. In a game, the combination of a casing having a floor inclined downwardly from front to rear of said casing, spherical counters for movement on said floor, scoring runways and a counter projecting runway on said floor, an operating runway, an operating sphere in said operating runway, a member for movement longitudinally of said operating runway for operating said operating sphere, impact transferring devices extending from the rear end of said operating runway to the rear end of said projecting runway, a movable gate across the outlet ends of said scoring runways, an arm carried by and extending from said gate, a bar extending through said casing and movable to operate said arm, and a support for said bar, said bar and said support comprising parts of coin controlled mechanism.

19. In a game, the combination of a casing having a floor inclined downwardly from front to rear of said casing, spherical counters for movement on said floor, scoring runways and a counter projecting runway on said floor, an operating runway, an operating sphere in said operating runway, a member for movement longitudinally of said operating runway for operating said operating sphere, impact transferring devices extending from the rear end of said operating runway to the rear end of said projecting runway, and a movable gate across the outlet ends of said scoring runways, said gate comprising a pivotally supported metal band having front, rear and end portions, said end portions engaging the pivotal supports of said gate, said gate having a first position holding said counters in said scoring runways and a second position releasing said counters from said scoring runways and retaining said counters between the front and rear portions of said gate.

20. In a game, the combination of a casing having a floor inclined downwardly from front to rear of said casing, spherical counters for movement on said floor, scoring runways and a counter projecting runway on said floor, an operating runway, an operating sphere in said operating runway, a member for movement longitudinally of said operating runway for operating said operating sphere, impact transferring devices extending from the rear end of said operating runway to the rear end of said projecting runway, a movable gate across the outlet ends of said scoring runways, said gate comprising a pivotally supported metal band having front, rear and end portions, said end portions engaging the pivotal supports of said gate, said gate having a first position holding said counters in said scoring runways and a second position releasing said counters from said scoring runways and retaining said counters

between the front and rear portions of said gate, a reciprocable bar extending through said casing to operate said gate, and a support for said bar, said bar and said support comprising parts of coin controlled mechanism.

It witness whereof, I hereunto subscribe by name this 14th day of March, A. D. 1932.

THOMAS S. HUTCHISON.
